UNITED STATES PATENT OFFICE.

WILLIAM C. BROWNELL, OF PUEBLO, COLORADO.

WINDMILL.

1,297,084.

Specification of Letters Patent. Patented Mar. 11, 1919.

Application filed October 22, 1917. Serial No. 197,952.

To all whom it may concern:

Be it known that I, WILLIAM C. BROWNELL, a citizen of the United States, residing at Pueblo, in the county of Pueblo and State 5 of Colorado, have invented certain new and useful Improvements in Windmills, of which the following is a specification.

This invention relates to wind mills, and its primary object resides in the provision 10 of a wind-actuated mechanism whose driving power is increased by the peculiar arrangement of a plurality of vane-wheels which coöperate to furnish motive power to a driven shaft.

15 A further object of the invention resides in the provision of an automatic governor for regulating the movement of the wind-wheels under varying wind pressures to maintain the driven-shaft at a substantially 20 uniform rate of speed.

Still other objects of the invention relate to details of construction and arrangement of parts, all of which will fully appear in the course of the following description.

25 In the accompanying drawings which illustrate an embodiment of my invention and in which similar characters of reference designate corresponding parts in the several views,

30 Figure 1 is a plan view of the operating mechanism of my improved wind-mill, in its preferred form,

Fig. 2, a section taken along the line 2—2, Fig. 1, and

35 Fig. 3, a section along the line 3—3, Fig. 2.

Referring to the drawings, 2 designates a suitably supported platform upon which is mounted a base 3 for the support of the operating parts of the wind-motor.

40 The base provides a step-bearing for a rotary standard 4 which has at its upper end, two axially aligned boxes 5 for the support of the driving shaft 6 of the motor.

45 The shaft carries at its opposite ends, the front and rear wind-wheels 7 and 8 the vanes of which are pitched in the same direction to impart a rotary motion to the shaft by action of the wind.

50 The driving shaft carries a beveled gear-wheel 9 which transmits its rotary motion to a corresponding wheel 10 at the upper end of an upright shaft 12 extending through aligned bores in the standard 4 and the base

55 3 and supported for rotation upon a suitable bearing 13.

The movement of the driven shaft is transmitted by means of a pair of beveled gear-wheels 14 and 15 to a crank-shaft 16 set at right angles thereto, for the operation of a 60 pump or other mechanical device, through the medium of a pitman 17.

An auxiliary wind-wheel 18 the vanes of which are pitched reversely with respect to those of the wheels 7 and 8 at the ends of 65 the driving shaft, is mounted for independent rotation in one of the bearings of the standard 4 by means of a tubular hub 19 through which the shaft 6 loosely extends.

The hub carries a beveled gear-wheel 20 70 which meshes with the before-mentioned gear-wheel 10 at the end of the driven shaft, at a point diametrically opposite to that at which it is engaged by the gear-wheel 9.

In order to maintain the wind-wheels in 75 facing relation to the air-currents, a feathering-rudder or tail 21 is provided which normally extends in parallel relation to the driving shaft, or at right angles to the parallel planes of rotation of the wind wheels. 80

The rudder is fastened at the end of a shank or stem 22 provided with a collar 23 for its rotary support upon a flange 24 at the lower end of the standard 4, and carrying a counterbalancing weight 25.

85 A governing rudder 26 of smaller area is mounted at the end of a shank 27 in rigid connection with the rotary standard, as best shown in Fig. 3 of the drawings, and extends at right angles to the primary rudder 90 21 with which it is connected by means of a leaf-spring 28.

This spring is at its ends attached to the shanks of the two rudders and is adapted to yield under pressure upon the governing 95 rudder 26.

In the operation of my improved wind-motor, the primary rudder 21 normally maintains the wind-wheels in the proper position to face the wind and thereby furnish 100 the motive power required for the rotation of the driven shaft.

The wind after acting on the front wheel 7 is deflected to act on the auxiliary wheel 18 for its rotation in the opposite direction 105 after which it engages the rear wheel 8 which is turned in the same direction as the first-mentioned wheel.

Since the gears on the shaft and the hub of the auxiliary wheel act upon the gear-wheel on the driven shaft at opposite points, the rotary movements of the three vane-

wheels are combined to impart a rotary motion to the driven shaft with a power greater than that obtained by either a single wheel or by two wheels the vanes of 5 which are pitched either in the same or in opposite directions.

Since the primary rudder extends normally in the direction of the wind, the governing rudder, being of smaller area, is under the same conditions kept in facing relation to the air currents, and the operating parts of the motor are thus under normal conditions held constantly in the proper position relative to the direction of the wind. 10 15 When, however, the force of the wind increases beyond a certain predetermined limit established by the resistance of the spring 28, its action upon the governing blade will cause the spring to yield, with the result 20 that the standard is moved about its axis and the vane wheels supported thereon are turned to face at an angle to the direction of the wind.

The motive power of the wheels is thus 25 automatically controlled in accordance with wind variations to effect the rotation of the driven shaft at a substantially uniform rate of speed.

I desire it understood that while I have 30 described and shown the embodiment of my invention which at present appears simplest and best adapted for its purpose, such minor changes in the details of construction and arrangement of the operating, transmission and controlling mechanisms of my improved wind-mill may be resorted to as are 35 within the scope of the following claims.

I claim:

1. In a wind mill, a driving shaft, wind 40 wheels affixed to the ends of said shaft, a driven shaft disposed at right angles to the driving shaft inwardly from the ends of the latter, a gear on said driven shaft, a gear on said driving shaft in mesh with the said 45 driven shaft gear, an auxiliary wind wheel

on said driving shaft and rotatable independently of the latter, and a gear carried by said auxiliary wind wheel and in mesh with the said driven shaft gear.

2. In a wind mill, a driving shaft, a yoke 50 having spaced bearings one of which supports said shaft near one end of the latter, a sleeve inclosing a portion of said shaft near the other end thereof and rotatably mounted in the other of said bearings, a bevel 55 gear carried by said sleeve, a bevel gear affixed to said driving shaft, a driven shaft rotatable in said yoke, a bevel gear affixed to said driven shaft and in mesh with the bevel gears on said sleeve and said driving shafts, 60 wind wheels secured to the ends of said driving shaft and having their blades pitched in the same direction, and a wind wheel affixed to said sleeve and having its blades pitched opposite to the inclination of 65 the blades of the first mentioned wind wheels.

3. In a wind mill, a driving shaft, a yoke having its arms embracing said driving shaft inwardly from the ends thereof, a driven shaft rotatable in said yoke, a bevel gear affixed to said driven shaft, a bevel gear affixed to said driving shaft and in mesh with the said driven shaft gear, a sleeve 70 inclosing and supporting said driving shaft near one end thereof and rotatable in one of said yoke arms, a bevel gear carried by said sleeve and in mesh with said driven shaft gear diametrically opposite the point of contact of the said driving shaft gear therewith, wind wheels affixed to the ends of 75 said driving shaft, and a wind wheel carried by said sleeve.

In testimony whereof I have affixed my signature in presence of two witnesses.

WILLIAM C. BROWNELL.
